MECHANICAL SILENT TAPPET

Clifton L. Stancliff, Bakersfield, Calif.

Application June 18, 1946, Serial No. 677,552

13 Claims. (Cl. 123—90)

1

An object of my invention is to provide a mechanical silent tappet which is an improvement over the form of my invention shown in my Patent No. 2,493,783, dated January 10, 1950. In the copending case, I disclose the spring means for rotating the two parts of the silent tappet as being disposed exteriorly of the parts. In the present form of the invention the spring means for rotating one part with respect to the other is confined within the area occupied by the two parts.

In all of the modifications illustrated in the present case, the two parts of the device have centering means for holding them in proper relation with the valve stem and with the valve tappet. The mechanical silent tappet is wafer-like in appearance and can be slipped between the valve stem and tappet or between the push rod and rocker arm, or between the valve stem and rocker arm, and will remain in position without any auxiliary fastening means being necessary.

The device is extremely simple in construction and is designed to be stamped out from sheet metal.

Other objects and advantages will appear in the following specification, and the novel features of the device will be particularly pointed out in the appended claims.

My invention is illustrated in the accompanying drawings forming a part of this application, in which:

Figure 1 is a top plan view of the silent tappet;
 Figure 2 is a top plan view of the upper plate;
 Figure 3 is a top plan view of the lower plate;
 Figure 4 is a section taken along the line IV—IV of Figure 1;

Figure 5 is a section taken along the line V—V of Figure 1;

Figure 6 is a transverse section taken along the line VI—VI of Figure 1;

Figure 7 is a view similar to Figure 6, but shows the two parts of the device in a slightly separated position;

Figure 8 is a top plan view of a modified form of the invention;

Figure 9 is a transverse section taken along the line IX—IX of Figure 8;

Figure 10 is a top plan view of the lower plate;

Figure 11 is a top plan view of the upper plate;

Figure 12 is a section taken along the line XII—XII of Figure 8;

Figure 13 is a top plan view of another modified form of the invention;

2

Figure 14 is a transverse section taken along the line XIV—XIV of Figure 13;

Figure 15 is a top plan view of the lower plate;

Figure 16 is a section taken along the line XVI—XVI of Figure 13;

Figure 17 is a section taken along line XVII—XVII of Figure 13;

Figure 18 is a view similar to Figure 17 but shows the parts slightly separated; and

10 Figure 19 is a top plan view of the upper plate. While I have shown only the preferred forms of my invention, it should be understood that various changes or modifications may be made within the scope of the appended claims without departing from the spirit and scope of the invention.

In carrying out my invention, I provide a mechanical silent tappet comprising two disc-shaped plates, an upper plate indicated at A in Figure 2, 20 and a lower plate indicated at B in Figure 3. The device is designed to be stamped out by means of a punch press and both Figures 1 and 2 show the upper plate provided with a plurality of raised portions 1 when looking at the top of the 25 plate, these portions being provided with cam-shaped undersurfaces 2 as illustrated in Figure 5. It will be noted that these cam-shaped surfaces have a gradual arc portion 2a and an abrupt curved portion 2b. The raised portions 1 are arranged in a circle about a common center 3 and as many of these portions as desired may be provided. In Figure 2 I show twelve of the raised portions, although I do not wish to be confined to any exact number.

30 35 Within the boundary defined by the circle of raised portions 1, I provide a second group of semi-cylindrical raised portions 4. In Figure 4 the interior of the raised portions 4 are designed to receive the upper halves of coil springs 5. Each 40 interior forms the upper half of a spring housing 6. The housing has a shoulder 7 formed at one end against which an end of the spring 5 contacts and the other end of the housing 6 has an inclined wall 8. The raised semi-cylindrical portions 4 are arcuate in shape and are arranged in a circle whose center is the same center 3 for the raised portions 1, see Figure 2. Referring to Figure 6, it will be seen that the upper plate A has a circumferential flange 9 that extends 45 downwardly and this flange has an inwardly turned rim 10 for a purpose presently to be described. It will be seen that the entire upper plate is designed so that it can be punch pressed.

50 Figure 3 shows the top of the lower plate and this plate is provided with a plurality of depress-

sions or recesses 11 of a number equal to the number of raised portions 1. The recesses 11 have cam-shaped inner surfaces 12 designed to co-operate with the cam-shaped surfaces 2, see Figure 5. Each surface 12 has a gradual arcuate portion 12a and an abrupt curve 12b. Figure 5 indicates how the gradual arc portion 2a is disposed at the opposite side of a ball C from that of the gradual arc portion 12a. When the disc A is rotated in the direction of the arrow shown in Figure 5 and the disc B rotated in the opposite direction, the ball C will act on the curved cam surfaces 2a and 12a for separating discs A and B a slight distance one from the other.

Again referring to Figure 3, it will be seen that the plate B has a plurality of elongated and arcuate shaped recesses 13 that are semicircular in cross section. These recesses cooperate with the spring-receiving housings 6 to accommodate the lower halves of the coil springs 5. Each recess 13 has a shoulder 14 against which the adjacent end of the spring 5 contacts and the opposite end of each recess is provided with an inclined wall 15. Figure 4 illustrates how the springs 5 are received within the cooperating portions 6 and 13 and how the ends of the springs contact with the shoulders 7 and 14 for yieldingly urging the discs A and B in opposite directions.

In assembling the parts, the balls C are placed in the recesses 11 and the springs 5 are placed in the recess 13. The upper plate A is now moved down upon the lower plate and the springs are received in the upper spring housing 6 while the balls are received in the cavities 2. The rim 19 is formed on the flange 9 after the plate A is mounted on the plate B. A felt washer 16 may be placed in a groove 17 that extends around the periphery of the plate B. This washer is for the purpose of retaining any oil that may be forced between two plates. It will be noted from Figures 3, 6 and 7 that the lower plate has a central oil opening 18 and this opening registers with an axial bore 19 provided in the tappet plug D.

From the foregoing description of the various parts of the device, the operation thereof may be readily understood.

The wafer thin device is placed between the tappet plug or lift D and the lower end of a valve stem E, or between the push rod and rocker arm, or stem and rocker arm on an overhead valve motor. The outer surfaces on the lower plate B which form the recesses 13 act as a centering means for the plate B on the tappet plug or lift as clearly shown in Figures 6 and 7. In like manner the projections or raised portions 1 on the upper plate A act as a centering means for correctly positioning the device with respect to the valve stem E. In mounting the device in place all that is necessary is to insert it between the tappet D and valve stem E. No fastening means of any kind is necessary.

During the operation of the engine it is assumed that during the interval of rest when the valve is seated and the tappet plug is in its lowermost position, the two plates A and B will have their central portions spaced slightly apart. When the tappet lifts the valve stem the springs 5 will first yield and permit the top plate A to rotate with respect to the bottom plate B until the central portions A1 and B1 contact with each other. The balls C will roll down to the lowest portions of the cam surfaces 12, while at the same time the highest portions of the cam sur-

faces 2 will contact with the tops of the balls to permit this movement. The two plates A and B will contact with each other at the central portions A1 and B1 before the valve starts to lift. 5 No metallic sound has been created during the movement of the central portions A1 and B1 into contact with each other because these portions already contact with the tappet and with the valve stem and the initial movement really consists in the closing of the space between the central plate portions and a slight rotational movement between the two plates. This is accompanied without any metallic noise because of the gradual cam surface portions 2a and 12a causing the central plate portions to come together with a film 10 of oil therebetween.

During the lifting of the valve by the tappet, the springs 5 are not used to lift the valve because the central plate portions A1 and B1 contact each 20 other and carry the entire load. As soon as the valve has completed its opening and closing movement and should the tappet continue to move away from the valve stem end so as to form a space therebetween, the plate A will instantly rotate with respect to the plate B due to the action 25 of the springs 5 and will move the arcuate cam surfaces 2a and 12a in the directions of the arrows shown in Figure 5 for causing the balls and the cam portions to spread the central plate portions apart. Since this movement instantly takes 30 place, there is no time period when the valve stem end will be spaced from the plate A and therefore there will be no tappet noise.

The bore 18 communicates with a forced feed 35 lubricating system, and the separation of the two central plate portions, as in Figure 7, will permit lubrication under pressure to be forced between the plates A and B and lubricate the balls and the springs. A thin film of lubricant will form 40 on the inner surfaces of the two plates and this will permit relative rotation between the plates the instant there is any separation between the tappet and the valve stem end.

In the drawings of Figures 1 to 7, inclusive, the 45 device is shown on a greatly enlarged scale for clarity. In actual practice the material will be $\frac{1}{16}$ to $\frac{1}{8}$ of an inch thick. The tappet screw is adjusted to take care of the thickness of the two plates, so that the total distance between 50 the tappet and valve stem will be .072 to .077. No other changes are necessary to be made. The valve stem is raised to insert the device.

The form shown in Figures 8 to 12, inclusive, is designed primarily for a Ford motor car engine. 55 This form is also of the punch press type. The lower plate F is shown in Figures 9 and 10 and it will be seen that this plate is provided with a plurality of hemispherically shaped recesses 20. In addition the rim 21 of the plate has struck 60 up portions 22 provided with radially extending shoulders 23. The top plate G has a central portion 24 designed to rest on the central portion 25 of the lower plate. Figure 11 shows the top plate provided with a plurality of spherical shaped 65 recesses 26 that are designed to overlie and normally register with the recesses 20 in the lower plate. Balls H are placed in the aligned recesses and when the top plate is rotated with respect to the bottom one, the spherical surfaces of the recesses will ride on the balls to cause them to separate the plates and automatically take up any space that might exist between the Ford lift J and the valve stem K.

The top plate has an annular spring-receiving 70 channel 27 formed adjacent to its rim, this chan-

nel overlying the rim 21 of the lower plate. Figure 11 shows projections 28 extending inwardly into the channel, these projections providing flat radially extending shoulders 29 against which the ends of springs 30 bear. Figure 12 shows a portion of the channel 27 with its inwardly extending projection 28 and the spring 30 is indicated as contacting with the flat shoulder 29. The other end of the spring contacts with the shoulder 23 formed by the upwardly extending projection 22.

Figure 8 illustrates the assembled device while Figure 9 shows how the rim 31 of the upper plate G extends beyond the channel 27 and encloses the periphery of the lower plate F. The portions 32 are struck inwardly from the rim 31 and prevent the plate G from being entirely removed from the plate F. If desired, a felt washer 33 may be placed adjacent to the rim 21, this washer or seal bearing against the rim 31 of the upper plate.

This device operates in the same manner as that disclosed for the device in Figures 1 to 7, inclusive. The springs 30 are placed outside of the balls H in this device rather than inside of the balls. The springs tend to rotate the two plates F and G with respect to each other and to cause the balls H to act on the spherical surfaces 20 and 26 to move the two plates apart as indicated in Figure 12 by the dash lines. The Ford valve stem K has a bushing 34 and a keeper 35. The silent mechanical tappet is placed between the Ford lift and the valve stem. The flange of the keeper 35 is received within the circular portion formed by the outer surface of the spring receiving channel 27. The lower plate F has a depression 36 on its under surface that will fit the conical top of the Ford lift J. No fastening means is necessary to secure the silent tappet in place. The device will clear the valve lifter guide shown at 37.

In Figures 13 to 19, inclusive, I show another modified form of silent tappet which makes use of cams rather than balls. In this form, the lower plate L has a central depression 38 on its under surface for receiving the top of the tappet plunger or lift M. The upper plate N has a central depression 39 in its upper surface that receives the end of the valve stem P. The two plates L and N have the same outer diameter and a retaining ring 40 is secured at 41 to the top plate and rotatably and slidably receives the bottom plate. The ring 40 has an inwardly extending flange 42 that prevents the entire removal of the plate N from the plate L.

Referring to Figure 15, it will be seen that the bottom plate L has a circle of arcuate-shaped recesses 43 that are semicylindrical in cross section. The top plate N has complimentary recesses 44 that register with the recesses 43 in the manner shown in Figure 16. A coil spring 45 is placed in each pair of registering recesses and one end of each spring will bear against the shoulder 46 in the lower plate while the other end of the spring will bear against the shoulder 47 in the top plate. The springs tend to rotate the two plates with respect to each other and to cause depending cams 48, that are carried by the under surface of the top plate, to ride on cam surfaces 49 provided in the upper surface of the lower plate. Figure 17 illustrates the position of one of the cams 48 when the two plates L and N are in contact with each other. Figure 15 shows the lower plate provided with a plurality of cam surfaces 49, while Figures 13 and 19 illus-

trate the top plate as being provided with a plurality of cams 48. In Figure 18 the two plates L and N have been moved apart a slight distance by the cams 48 riding up on the cam surfaces 49.

In operation this form of the invention performs in the same manner as the other two forms, except that the cams 48 are integral with the top plate N and slide over the cam surfaces 49 in the lower plate. Any spacing that might exist between the top of the tappet M and the bottom of the valve stem P will be automatically taken up by the instant movement of the two plates away from each other, because of the springs 45. This form of the device may be lubricated by a central bore 50 in the tappet conveying a lubricant through an opening 51 provided in the bottom plate L. When the plates are spaced apart, the lubricant will flow therebetween and will lubricate the opposed surfaces as well as the cam-shaped recesses 49 and the projections 48.

I claim:

1. A mechanical silent tappet comprising two disc-shaped members arranged in confronting relation and adapted to be placed between an operating part and an operated part of a valve-operating mechanism, the confronting faces of the members having registering recesses with cam-shaped surfaces that extend from the said faces to spaced distances therefrom, a ball bearing placed in each pair of recesses, the pairs of recesses being arranged in a circle about the center of the members and the cam surfaces of each pair being such that a relative rotation between the members in one direction will cause the balls to ride on the cam surfaces to separate the members, and spring means confined within the perimeters of the members for yieldingly urging them in the direction just mentioned, said spring means being disposed within the area defined by the ball-bearing recesses and including a plurality of arcuate-shaped cavities formed in each member, the cavities in one member cooperating with those in the other to provide pairs of cavities, and a coil spring mounted in each cavity pair, each cavity having a face against which an end of the spring bears, the faces in each pair contacting opposite ends of the spring, the springs yieldingly exerting a rotative force on the members for causing the balls to ride on the cam surfaces to separate the members.

2. A mechanical silent tappet comprising two disc-shaped members made of sheet metal and having central portions arranged in confronting relation, each member having portions formed into cam-shaped recesses, the recesses in one member registering with those in the other to form pairs of ball-receiving compartments that are arranged in a circle whose center is the aligned centers of the members, balls placed in the compartments, each member also having semi-cylindrical arcuate-shaped cavities formed therein, the cavities in one member registering with those in the other to form pairs of spring-receiving compartments arranged in a circle that lies within and is concentric to the ball-receiving compartments, springs mounted in the spring-receiving compartments, the cavities in one member having shoulders bearing against one end of the springs and the cooperating cavities in the other member having shoulders bearing against the other end of the springs, the springs yieldingly exerting a rotative force on the members for causing the balls to ride on the cam surfaces to separate the members.

3. A mechanical silent tappet comprising two

disc-shaped members made of sheet metal and having central portions arranged in confronting relation, each member having portions formed into cam-shaped recesses, the recesses in one member registering with those in the other to form pairs of ball-receiving compartments that are arranged in a circle whose center is the aligned centers of the members, balls placed in the compartments, each member also having semi-cylindrical arcuate-shaped cavities formed therein, the cavities in one member registering with those in the other to form pairs of spring-receiving compartments arranged in a circle that lies within and is concentric to the ball-receiving compartments, springs mounted in the spring-receiving compartments, the cavities in one member having shoulders bearing against one end of the springs and the cooperating cavities in the other member having shoulders bearing against the other end of the springs, the springs yieldingly exerting a rotative force on the members for causing the balls to ride on the cam surfaces to separate the members, one member having a peripheral rim for slidably receiving the periphery of the other member, and means carried by the rim for limiting the separation between the members.

4. A mechanical silent tappet comprising two disc-shaped members made of sheet metal and having central portions arranged in confronting relation, each member having partial spherical-shaped recesses, the recesses in one member registering with those in the other to form pairs of ball-receiving compartments that are arranged in a circle whose center is the aligned centers of the members, balls placed in the compartments, one member having a circular spring-receiving channel that surrounds the circle of ball-receiving compartments, the channel having inwardly-extending stops, the other member having a portion forming a closure for the channel with stops extending inwardly into the channel for cooperating with the other stops to provide pairs of stops, and coil springs placed in the channel and having their ends bearing against the pairs of stops for yieldingly exerting a rotative force on the members for causing the balls to ride on the cam surfaces of said recesses to separate the members.

5. A mechanical silent tappet comprising two disc-shaped members made of sheet metal and having central portions arranged in confronting relation, each member having partial spherical-shaped recesses, the recesses in one member registering with those in the other to form pairs of ball-receiving compartments that are arranged in a circle whose center is the aligned centers of the members, balls placed in the compartments, one member having a circular spring-receiving channel that surrounds the circle of ball-receiving compartments, the channel having inwardly-extending stops, the other member having a portion forming a closure for the channel with stops extending inwardly into the channel for cooperating with the other stops to provide pairs of stops, coil springs placed in the channel and having their ends bearing against the pairs of stops for yieldingly exerting a rotative force on the members for causing the balls to ride on the cam surfaces of said recesses to separate the members, the channel having an extended circular side for slidably receiving the periphery of the other member, and means carried by the circular side for limiting the separation between the two members.

6. A mechanical silent tappet comprising two

disc-shaped members and having central portions adapted to contact each other so as to transmit thrust from one member to the other, the members having centrally disposed recesses in their outer surfaces adapted to receive an operating and an operated part of a valve-actuating mechanism, both members having arcuate and semi-cylindrical recesses in their confronting surfaces, the recesses in one member registering with those in the other substantially throughout their lengths to form pairs of recesses, coil springs received in the pairs of recesses and extending into both, one recess of each pair having an end wall contacting with an end of the spring received in the recess and the other recess of the same pair having an end wall contacting with the other end of the same spring, one member having a plurality of cams arranged in a circle that encloses the pairs of recesses, the other member having a plurality of cam-shaped concave surfaces that receive the cams, said cams when at the lowest points of the concave surfaces permitting the central portions of said members to contact each other, said springs yieldingly exerting a rotative force on the members for causing the cams to ride on the concave surfaces for separating the members.

7. A mechanical silent tappet comprising two disc-shaped members and having central portions adapted to contact each other so as to transmit thrust from one member to the other, the members having centrally disposed recesses in their outer surfaces adapted to receive an operating and an operated part of a valve-actuating mechanism, respectively, both members having arcuate and semi-cylindrical recesses in their confronting surfaces, the recesses in one member registering with those in the other substantially throughout their lengths to form pairs of recesses, coil springs received in the pairs of recesses and extending into both, one recess of each pair having an end wall contacting with an end of the spring received in the recess and the other recess of the same pair having an end wall contacting with the other end of the same spring, one member having a plurality of cams arranged in a circle that encloses the pairs of recesses, the other member having a plurality of cam-shaped concave surfaces that receive the cams, said cams when at the lowest points of the concave surfaces permitting the central portions of said members to contact each other, said springs yieldingly exerting a rotative force on the members for causing the cams to ride on the concave surfaces for separating the members, a ring carried by the periphery of one member and slidably receiving the periphery of the other, and means carried by the ring for limiting the separation between the members.

8. A mechanical silent tappet comprising two disc-shaped members arranged in confronting relation, the members having centrally disposed recesses in their outer surfaces adapted to receive an operating and an operated part of a valve-actuating mechanism, respectively, both members having arcuate and semi-cylindrical recesses in their confronting surfaces, the recesses in one member registering with those in the other substantially throughout their lengths to form pairs of recesses, coil springs received in the pairs of recesses and extending into both, one recess of each pair having an end wall contacting with an end of the spring received in the recess and the other recess of the same pair having an end wall contacting with the other end of the same spring, one member having a plurality of cams arranged in a circle that encloses the pairs of recesses, the other member having a plurality of cam-shaped concave surfaces that receive the cams, said cams when at the lowest points of the concave surfaces permitting the central portions of said members to contact each other, said springs yieldingly exerting a rotative force on the members for causing the cams to ride on the concave surfaces for separating the members, a ring carried by the periphery of one member and slidably receiving the periphery of the other, and means carried by the ring for limiting the separation between the members.

plurality of cams arranged in a circle that encloses the pairs of recesses, the other member having a plurality of cam-shaped concave surfaces that receive the cams, said springs yieldingly exerting a rotative force on the members for causing the cams to ride on the concave surfaces for separating the members, a ring carried by the periphery of one member and slidably receiving the periphery of the other, and means carried by the ring for limiting the separation between the members, the member contacting with one of said parts of said mechanism having a lubricant receiving opening therein that registers with a lubricant bore in that part.

9. A mechanical silent tappet comprising two wafer-like members arranged one above the other in confronting relation and movable into face-to-face contact so as to transmit thrust from one member directly to the other, and adapted to be interposed between operating and operated parts of a valve-actuating mechanism; the upper member having a depending annular flange on its periphery having a dust-tight and sliding telescoping fit with the periphery of the lower member; the flange defining a downwardly-facing opening at its bottom through which the lower member is insertable; camming means confined within the peripheries of the members for separating them when one member is rotated relative to the other in one direction; the camming means being shaped to gradually bring the members into sliding contacting relation with a spiral movement when the direction of rotation is reversed; and spring means for rotating the members in the direction to separate the members to maintain them continually in engagement with the operated and operating parts, respectively, of the valve-actuating mechanism.

10. A mechanical silent tappet comprising two wafer-like members arranged one above the other in confronting relation, and adapted to be interposed between operating and operated parts of a valve-actuated mechanism; the upper member having a depending annular flange on its periphery having a dust-tight and sliding telescoping fit with the periphery of the lower member; the flange defining a downwardly-facing opening at its bottom through which the lower member is insertable; camming means confined within the peripheries of the members for separating them when one member is rotated relative to the other in one direction; the camming means being shaped to gradually move the members into sliding contacting relation with a spiral movement when the direction of rotation is reversed; and a plurality of independent springs arranged around the extended axes of the operating and operated parts of said mechanism, and anchored to the members to provide rotary thrust between the members at several points around said axes.

11. A mechanical silent tappet comprising two wafer-like members arranged one above the other in confronting relation, and adapted to be interposed between operating and operated parts of a valve-actuated mechanism; the upper member having a depending annular flange on its periphery having a dust-tight and sliding telescoping fit with the periphery of the lower member; the flange defining a downwardly-facing opening at its bottom through which the lower member is insertable; camming means confined within the peripheries of the members for separating them when one member is rotated relative to the other in one direction; the cam-

ming means being shaped to gradually move the members into sliding contacting relation with a spiral movement when the direction of rotation is reversed; and a plurality of independent springs arranged around the extended axes of the operating and operated parts of said mechanism, and anchored to the members to provide rotary thrust between the members at several points around said axes; said camming means including ball bearings disposed between the members and around the extended axes of the operating and operated parts of said mechanism and providing substantially uniform ball bearing support between the members.

12. A mechanical silent tappet comprising two disc-shaped members movable into face-to-face contact so as to transmit thrust from one member directly to the other, and adapted to be placed between an operating part and an operated part of a valve-actuating mechanism; the confronting faces of the members having registering recesses with cam-shaped surfaces that extend from said faces to a spaced predetermined distance therefrom; a ball bearing disposed in each pair of recesses; the pairs of recesses being arranged about the center of the members; the cam surfaces of each pair of recesses being sloped oppositely so that a relative rotation between the members in one direction will cause the balls to ride upon the cam surfaces to separate the members; and spring means for yieldingly urging the members in the direction just mentioned; the recesses having sufficient depth to entirely receive the balls and thus allow the members to come into face-to-face contact with one another when the members are rotated into a predetermined position relative to one another and thus relieve the balls from thrust.

13. A mechanical silent tappet comprising two disc-like members arranged one above the other, and adapted to be placed between an operating and an operated part of a valve-actuating mechanism; the upper member having a depending annular flange on its periphery having a dust-tight and sliding telescoping fit with the periphery of the lower member; the flange defining a downwardly-facing opening at its bottom through which the lower member is insertable; the confronting faces of the members having registering recesses with cam-shaped surfaces that extend from said faces to a spaced predetermined distance therefrom; a ball bearing disposed in each pair of recesses; the pairs of recesses being arranged about the centers of the members; the cam surfaces of each pair of recesses being sloped oppositely so that a rotation between the members in one direction will cause the balls to ride up on the cam surfaces to separate the members; and a plurality of independent springs for yieldingly urging the members in the direction just mentioned to separate the members.

CLIFTON L. STANCLIFF.
